UNITED STATES PATENT OFFICE.

THOMAS J. SIMPSON, OF WORTHINGTON, MINNESOTA.

SPARK ARRESTER AND CONDUCTOR.

SPECIFICATION forming part of Letters Patent No. 334,680, dated January 19, 1885.

Application filed October 7, 1885. Serial No. 179,929. (No model.)

To all whom it may concern:

Be it known that I, THOMAS J. SIMPSON, a citizen of the United States, and a resident of Worthington, in the county of Nobles and State of Minnesota, have invented certain new and useful Improvements in Spark-Arresters and Smoke-Conductors; and I do hereby declare that the following is a full, clear, and exact description of the invention, which will enable others skilled in the art to which it appertains to make and use the same, reference being had to the accompanying drawings, which form a part of this specification.

My invention relates to an improved apparatus for arresting the sparks and conducting away the smoke, gas, soot, &c., issuing through the smoke-stack of railroad-locomotives, whereby the passengers and merchandise in a train may be saved from the inconvenience and danger of injury or destruction by reason of the incandescent or other cinders and smoke from the locomotive passing into or upon the cars or other railroad rolling-stock.

My invention also greatly aids to prevent local conflagrations caused by the ejection of incandescent particles from locomotives while passing through fields or land, or in the neighborhood of houses or other buildings during the dry or heated season.

To these ends my invention consists, broadly, in first conducting the sparks, smoke, &c., from the smoke-stack of the locomotive through a flue having a spark box or arrester of peculiar construction, in which the sparks are caught and retained, the smoke, gas, soot, &c., passing on through pipes extending on each side of the steam and sand domes of the locomotive to enter at each eye of a suction and forcing fan, located, preferably, on the rear portion of the locomotive, and preferably operated by a small separate engine in the cab, which receives steam from the steam-dome of the engine proper or main engine. The smoke, gas, soot, &c., are then forced by the said fan through the conducting-tube, which is formed of sections connected by flexible or movable couplings of peculiar construction, over the top of the tender and the several cars, and are finally discharged at the rear end of the train, at which point the conducting-tube is pro-

vided with a shield or protecting-cap of peculiar construction, which serves to assist the draft and at the same time protect the rear end of the said tube from the direct force of the wind, which might be blowing in the same direction or at an angle toward the direction in which the train is moving.

My invention further consists in surrounding the said smoke-conducting pipes with larger tubes having flaring forward ends, and arranged in winter to conduct pure vital air, which is heated by passing around the smoke-conducting tubes, into the interior of the cars through a valve or duct opening from the said vital-air pipes into the cars at points near the roof of the same.

My invention further consists in the peculiar construction and arrangement of the reversible damper, which will be hereinafter described.

My invention likewise consists in utilizing the exhaust-steam by conveying it in suitable pipes to the smoke-conducting tube, which it enters immediately to the rear of the exhaust and forcing fan, thereby materially increasing the draft through the said conducting-tube.

My invention furthermore consists in certain combinations and sub-combinations and in the peculiar construction and arrangement of parts thereof, which will be hereinafter fully described, and pointed out in the claims.

Referring to the annexed drawings, Figure 1 is a side elevation of a railroad-locomotive with a tender and two cars attached, with my improvements applied thereto, the several couplings (which are shown as arranged in winter) being shown partly in elevation and partly in section, and parts of the outer casing of the cars and tender being broken away to illustrate the construction and arrangement of the several parts. Fig. 2 is a side elevation of the same, taken from the opposite side to that shown in Fig. 1, showing the arrangement of the couplings in summer. Fig. 3 is a perspective top view of the locomotive, showing more clearly the arrangement of the double smoke-conducting pipes and the adjacent parts. Fig. 4 is a perspective detail view of the shield or protecting-cap, which is secured to the rear end of the smoke-conducting

tube; and Figs. 5 and 6 are sectional detail views of two of the couplings, which will be hereinafter described.

The same letters of reference indicate corresponding parts in all the figures.

Referring to the several parts by letter, A indicates the locomotive, B the tender, and C C the cars, of a train to which my invention is shown as applied. The smoke-stack D of the engine is formed near its lower end and at the point where it communicates with the forward portion of the smoke-conducting tube in which the spark-arrester is situated, with the circular chamber E, in which is centrally pivoted or hung the reversible damper F. This curved or triangular damper is formed with the two wings G G, which connect at the center at an angle, as shown, the object of this peculiar construction being that when the 15 damper is turned by means of the operating-rod f, running back to the cab, either to cut off exit into the smoke-stack proper and give free access into the smoke-conducting pipe or tube, as shown in full lines in the drawings, or else turned, as shown in dotted lines, to close the access into the smoke-conducting tube and open the way to the smoke-stack of the locomotive, the pressure of the smoke, &c., against the outer convex side of the said 20 damper will operate to force it and hold it more closely in its operative position, thereby giving it great efficiency in operation, as will be readily understood.

The sparks, smoke, gas, &c., pass, when the 35 reversible damper is in its normal position, as shown in full lines in the drawings, into that portion of the conducting-tube immediately adjoining the said circular chamber, and in which the spark box or arrester is located. 40 This box H is of the peculiar form shown in the drawings, having the perpendicular front side and the sloping rear side. It will be seen that as the sparks, together with the smoke, &c., pass up through the circular chamber E 45 they will strike against the top of the flue or tube nearly over the spark-box, and will be thrown either directly down into the said spark-box, or, striking against its perpendicular front side, will then fall to the bottom 50 thereof.

Immediately in front of the spark-box the smoke-conducting tube is divided; or two tubes, K K, are employed, one extending on each side of the steam and sand domes, as 55 shown in the perspective view, Fig. 3, of the drawings, the combined capacity of these two tubes being fully as great, or greater, than the capacity of the smoke-stack.

On the rear portion of the locomotive is situated a suction and forcing fan, I, turning in a suitable fan-chamber, J, and receiving power, preferably, from a small separate engine in the cab, which in turn receives steam from the steam dome of the engine. I do not wish 65 to confine myself to any particular method of operating the said fan, as such method forms

no part of my invention. The rear inwardly-curved ends of the two conducting-tubes K K communicate directly with each eye of the fan, as shown in the perspective view, each eye of the fan being surrounded with the usual circular opening.

The exhaust-steam is led from each side of the locomotive through suitable pipes, L L, and admitted into the discharge-tube M of the fan on each side thereof, as shown, the said discharge-tube of the fan forming a part of the smoke-conducting tube proper. It will be seen that by this arrangement I utilize the exhaust-steam, the discharge of which through the conducting-tube serves to materially increase the draft through the said tube, and would serve to create a certain amount of draft through the said tube even if the fan were not in motion.

The open end of the discharge-tube M of the fan is flexibly or movably connected, by means of the peculiar coupling device, which will be now described, to the forward end of the first section of the smoke-conducting tube, the said tube being made in sections, one for each car and for the tender, being supported on the tops thereof, as shown. Each end of each of the sections of the said smoke conducting tube is provided with an outwardly-extending circular flange, N, which may be formed integral with the pipe, or may consist of a flaring collar, secured in position by suitable pins or screws, as shown in the detail view, Fig. 5, of the drawings. The adjacent flanged ends of two sections of the smoke conducting tube are movably connected, yet in such a manner as to prevent any escape of smoke, &c., at the point of coupling, by means of the coupling device O, which consists of a sleeve or short tube of such a diameter as to fit around the flanged ends of the tube sections and prevent the escape of smoke, &c., therefrom, being held in its operative position by the spring-catches P P, which, while holding the coupling-sleeve in its operative position, and preventing the ends of the tubes from slipping or working out of the same, yet are so arranged as to permit of considerable movement of the ends of the sections inside of the coupling-sleeve as the train rocks and swings from side to side when in motion. These spring catches P are preferably constructed of a single spring-bar, Q, pivoted at its center upon the top of the coupling-sleeve, and provided, near each of its free ends, with a catch, R, which extends down through a suitable opening in the said sleeve near the end of the same, and thereby prevents the flanged ends of the tube-sections from working out of the said coupling. The interior diameter of the coupling-sleeve being exactly equal to the diameter of the flanges on the ends of the tube-sections, it will be seen that no matter how much the ends of the tube-sections may move in the couplings 120 while the train is in motion, yet no smoke, &c., will be able to escape. The coupling is sur-

rounded and inclosed in a sack, S, of asbestos or other non-combustible material, which is held in position at each end by the adjustable circular hoops or fastening devices T T, as shown in Fig. 1 of the drawings. It will be understood that the contiguous ends of all the sections of the smoke-conducting tubes are connected by the above-described coupling.

Each section of the smoke conducting tube 10 which extends over a car is inclosed in a tube, U, of larger diameter, which I prefer to denote, for the sake of clearness, as "pure-air" or "vital-air" tubes, each of the said vital-air tubes being formed at its forward end with 15 the flaring mouth piece V, which serves to, in a manner, collect the pure vital air when the train is in motion. The rear end of each vital-air tube is in winter closed by a cap, W, which, as shown, fits closely around the smaller 20 smoke-conducting tube, and also around the rear end of the vital-air pipe, thereby completely closing the rear end of the said pipe. Each vital-air pipe communicates through a small duct or flue, near its rear end, with the 25 interior of the car, each of the said ducts or flues being controlled by a valve, X, which is adapted to be opened in winter and closed in summer. It will be seen that when the train is in motion the pure vital air will enter the 30 flaring mouth of each vital-air pipe, and passing through the same through the space between the said outer pipe and the inclosed smoke-conducting pipe or tube will become heated by contact with the said inclosed 35 smoke-pipe, and this pure heated air will be then discharged through the flues Y into the interior of the car, thereby effectually ventilating the cars and furnishing them in winter with much needed pure, vital, and warmed 40 air.

To the rear end of the rear section of the smoke-conducting tube is secured the shield or protecting-cap Z, as shown, having the straight sides and the upward and outwardly 45 slanting back, the top or upper edge of which extends somewhat above the mouth of the rear tube-section. The object of this protection-cap is to prevent the wind from blowing into the end of the smoke-conducting tube, which 50 would prevent or obstruct the draft, and also to give an upward direction to the smoke, which is accomplished by the slanting back of the said cap. The arrow, which I have numbered 1 in Fig. 1 of the drawings, shows 55 how the air would pass down the rear slanting end of the said cap. Arrow No. 2 shows how the packed air would be drawn up through the said cap, and arrow No. 3 shows the direction taken by the smoke and steam when 60 issuing from the conductor-tube, from which it will be seen that the air passing up through the cap, as just described, (owing to the peculiar construction of the said cap,) will materially assist in directing the course taken by the 65 smoke and steam on its exit from the conveyer or conductor tube.

The caps which in winter serve to close the rear ends of the vital-air pipes are in summer removed, and a flaring mouth-piece, A', is secured to the rear end of each of the said 70 pipes, the valves X of the flues Y being closed to prevent the heated air from entering the cars, which, of course, is undesirable in summer. This arrangement is clearly illustrated in Fig. 2 of the drawings. It will be seen 75 that by this arrangement the air passing in between the two pipes and escaping at the rear end of the pure-air pipe will operate to cool the exterior of the smoke and gas tube, and 80 thereby prevent it from heating the upper portion of the cars.

By reference to Fig. 2 of the drawings it will be seen that the smoke-conducting tube is provided immediately above the spark-box with a port or opening, B', which is normally closed by a slide-valve, C', operated by means of a rod, D', from the cab of the locomotive. The object of this arrangement is as follows: When the train nears a station 90 and begins to slow up, the engineer reverses the damper, (which has been previously described,) so as to cause the smoke, &c., to pass up through and out of the smoke-stack, and at the same time pulls the rod D' to open 95 the slide-valve C'. The pure air then rushes in through the port or opening B', and through the influence of the suction and forcing fan and the exhaust-steam passes entirely through the smoke-conducting tube, so as to effectually clear the same from all smoke, gas, soot, &c., as will be readily understood.

The spark-box, previously described, is formed with an opening at its bottom, which is normally closed by a slide, E', so that by 105 opening the said slide the cinders are permitted to roll down into any suitable receptacle.

The smoke-conducting tube by its peculiar construction and its air tight flexible couplings becomes an air-tight tube, with no outside air-currents entering therein, and when the train is moving forward the air, gas, and smoke inside of this air-tight tube are made to move in the opposite direction to that in 110 which the train is going, by reactive force, which will cause a direct air-draft from the furnace, this draft being assisted by the combined suction and forcing fan, and, further, by the exhaust-steam, this construction of the 115 smoke-conducting tube producing a smooth strong draft, without any of that objectionable jerking motion which would be caused by the exhaust steam if the smoke-conducting tube were not so constructed.

From the foregoing description, taken in connection with the accompanying drawings, the construction, arrangement of parts, and operation of my invention will be readily understood without requiring further explanation. The advantages of my invention are 130 obvious. It will be seen that by constructing

the reversibly-angular damper of the form shown and described, the pressure of the current of smoke, &c., will operate to press and hold the damper more firmly in its adjusted position. By constructing the spark-box of the peculiar shape shown and described, and locating it at the particular point specified, the sparks and cinders will be effectually arrested and prevented from being sucked through the smoke-conducting flue. By conveying the exhaust-steam through suitable pipes into the smoke-conducting tube, as described and shown, I succeed in utilizing the exhaust-steam and cause it to materially assist the draft through the smoke-conducting tube. By employing the combined suction and forcing fan and arranging it in the smoke-conducting tube in the manner shown and described, with the double or diverging forward portion of the said tube communicating with the eyes of the fan box or chamber, I secure a perfect draft entirely independent of the direction which the wind may be blowing, as no wind enters the smoke conducting tube, as is usually the case. The peculiar coupling devices shown for connecting the flanged ends of the smoke-conducting tube-sections allow for all the jar and movement caused by the train when in motion, and at the same time effectually prevent the escape of any smoke, gas, &c., at the points where the sections are coupled together. The peculiarly-arranged vital-air pipes encircling the smoke-conducting tube sections convey pure warmed vital air into the interior of the several cars in winter, thereby assisting in ventilating the same at a season when this pure air is especially needed, all of the doors and windows of the cars being at this season normally closed. The peculiar protecting-cap at the rear end of the smoke-conducting tube materially assists the draft or exit of the smoke, &c., and at the same time prevents the wind from blowing into the end of the said tube, as before stated; and, finally, by constructing the port or opening in the smoke-conducting tube just above the spark-box, and providing the said opening with the slide-valve, the smoke-conducting tube may be effectually cleaned by the outer cold air when the train arrives at a station, as previously described.

Having thus described my invention, what I claim, and desire to secure by Letters Patent of the United States, is—

1. The combination, with the locomotive provided with the circular chamber communicating both with the smoke-stack and with the smoke-conducting tube, of the herein-described angular damper, formed of the two wings meeting at an angle to adapt it to be held more firmly in its adjusted position by the pressure of the current of smoke, &c., as the latter enters either the smoke-stack or the smoke-conducting tube, substantially as shown and set forth.

2. The combination, with the smoke-con-

ducting tube for railroad-locomotives and the combined suction and forcing fan arranged to create or assist the draft through the said tube, of the exhaust-steam pipes arranged to convey the exhaust-steam into the said smoke-conducting tube, for the purpose set forth.

3. The combination, with the smoke-conducting tube for railroad-locomotives, of the exhaust-steam pipes arranged to convey the exhaust-steam into the said smoke-conducting tube, for the purpose set forth.

4. The combination, with the smoke-conducting tube for railroad-locomotives and the combined suction and forcing fan arranged to create or assist the draft through the said tube, of the exhaust-steam pipes arranged to convey the exhaust-steam from each side of the locomotive and discharge it into the said smoke-conducting tube to the rear of the said fan, substantially as set forth.

5. The combination, with the smoke-stack, of the smoke conducting tube communicating therewith and formed at a point immediately to the rear of its curved forward end with the herein-described spark box or arrester having the perpendicular rear side, and arranged to operate in the manner and for the purpose shown and set forth.

6. The combination of the combined suction and forcing fan located on the rear portion of the locomotive, the double smoke-conducting tubes arranged to conduct the smoke, gas, &c., from the smoke-stack of the locomotive and discharge the same into each eye or central end opening of the fan-chamber or casing, and the single smoke-conducting tube extending rearwardly from the said fan, substantially as described, for the purpose set forth.

7. The combination, with the tube-sections having the flanged ends, of the herein-described coupling devices, consisting each of a coupling-sleeve of suitable length having its interior diameter exactly equal to the exterior diameter of the said flanged ends of the tube-sections, and provided with the spring-catches arranged to operate as described, substantially as set forth.

8. The combination, with the tube-sections having the flanged ends and the coupling-sleeves having the retaining spring-catches, of the herein-described non-combustible sack or envelope, adapted to be secured in its operative position by the spring-hoops or catches secured adjustably around each end of the same, as and for the purpose shown and described.

9. The combination, with the smoke-conducting tube, of the herein-described protecting-cap, secured to the rear open end thereof, and having the slanting back and the open front and top portions, and adapted to operate in the manner and for the purpose shown and set forth.

10. The combination, with the smoke-conducting tube having the spark-box at its for-

ward end and the combined suction and forcing fan arranged, as described, in the said tube to create or assist the draft, of the valve-controlled port or opening formed immediately above the said spark-box in the side of the smoke-conducting tube, for the purpose set forth.

11. The combination of the herein-described air-tight smoke-conducting tube, communicating at its forward end only with the furnace of the locomotive, the combined suction and forcing fan arranged, as described, in the said

tube to assist the draft, and the exhaust-steam pipes arranged to convey the exhaust-steam into the said smoke-conducting tube, as and for the purpose shown and set forth.

In testimony that I claim the foregoing as my own I have hereunto affixed my signature in presence of two witnesses.

THOMAS J. SIMPSON.
